UNITED STATES PATENT OFFICE.

THOMAS KOCHKA, OF JERSEY CITY, NEW JERSEY.

TOY BOWLING-ALLEY.

SPECIFICATION forming part of Letters Patent No. 358,359, dated February 22, 1887.

Application filed December 11, 1886. Serial No. 221,246. (No model.)

To all whom it may concern:

Be it known that I, THOMAS KOCHKA, a citizen of the United States, residing at Jersey City, Hudson county, State of New Jersey, 5 have invented an Improved Toy Bowling-Alley, of which the following is a specification.

This invention relates to a toy bowling-alley in which the pins are attached to a slide, so that they may all be set up at the same time.

10 The bowling-alley is provided with a propeller of peculiar construction, all as herein-after more fully pointed out.

In the accompanying drawings, Figure 1 is a top view of my improved bowling-alley. 15 Fig. 2 is a bottom view of the same. Fig. 3 is a longitudinal central section of the same; and Fig. 4 is a detailed top view of the propeller, showing it partly cocked.

The letter *a* represents the game-board, upon 20 which are placed nine (more or less) pins, *b*. Beneath each pin *b* the board *a* is perforated for the passage of a string, *c*, attached at one end to the base of pin *b* and at the other end to a slide, *d*, operated by rod *e*. Each string 25 *c* passes over a roller, *f*, journaled in stationary bearings *g* beneath board *a*. *h* are springs for drawing the slide *d* back after it has been pulled out.

After the pins *b* have been thrown down by 30 means of a ball shot from the propeller, hereinafter described, the rod *e* is drawn out to pull string *c*, and to thereby set up pins *b*. The rod *e* is then released, the slide will be drawn back, and thus the strings will be left

sufficiently loose to permit the pins to be 35 thrown over.

The propeller consists of a swiveled perforated plate, *i*, through which pass two bars, *j*, attached at one end to handle *k*, carrying at the other end the propelling-chamber *l*. Between such chamber and plate *i* the bars *j* are surrounded by spiral springs *m*. By drawing the handle out the springs are contracted to propel chamber *l* and the charge contained therein forward upon the release of the handle. 45 It will be seen that this propeller may be revolved so as to be pointed to any direction.

I am aware of Patent No. 149,418, granted to T. A. Schwennesen, April 7, 1874, which shows a toy bowling-alley in which the pins 50 are connected to strings by means of which they may be set up. I am also aware of Patent No. 153,236, granted to J. Butt, July 21, 1874, which shows a toy bowling-alley having a spring-plunger that turns upon a pivot. These 55 constructions I do not claim; but

I do claim—

The combination of perforated game-board *a* with pins *b*, strings *c*, slide *d*, rod *e*, spring *h*, and with rollers *f*, journaled in stationary 60 bearings *g* beneath board *a*, the strings *c* being attached at one end to pins *b* and at the other end to slide *d*, and passing around rollers *f*, substantially as specified.

THOMAS KOCHKA.
